UNITED STATES PATENT OFFICE.

JOHN W. GILBERT AND JOHN A. PRATHER, OF ATHENS, TENNESSEE,
ASSIGNORS OF ONE-HALF TO JOSEPH J. IVINS.

CAR-COUPING.

SPECIFICATION forming part of Letters Patent No. 240,017, dated April 12, 1881.

Application filed September 10, 1880. (No model.)

To all whom it may concern:

Be it known that we, J. W. GILBERT and J. A. PRATHER, citizens of the United States, residing at Athens, in the county of McMinn 5 and State of Tennessee, have invented certain new and useful Improvements in Car-Couplings; and we do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 The object of this invention is to construct a simple and effective car-coupling, more especially intended for freight-cars, so designed that it will automatically couple, and that it may be uncoupled from the top of the car, as 20 well as from either side thereof, without going between the cars.

To these ends the invention consists in certain combinations set forth in claims at the close of this specification, and made up out of 25 mechanical devices of which the following are the principal: A draw-head longitudinally slotted both at top and bottom, two grooved vertical guide-posts on the draw-head, a coupling-pin constructed with a cross-bar at its upper 30 end, adapted to slide up and down in the grooved guides and to serve as a pivot on which the pin can swing, a lifter-rod reaching to the top of the car and connected, through a chain, to the head of the coupling-pin, two 35 levers extending from the lifter-rod, to which they are pivoted to opposite sides of the car. Minor devices are also used to make up some of the combinations.

In order that our invention may be clearly 40 understood we have illustrated it in the annexed drawings, and will proceed to describe the best form thereof at present known to us.

Figure 1 is a perspective view of our improved coupling applied to a box freight-car, 45 showing a link in the draw-head engaged by the coupling-pin. Fig. 2 is a sectional end elevation, showing the coupling-pin lifted so as to free the link; and Fig. 3 is a perspective view of the coupling-pin detached.

50 Similar letters refer to similar parts throughout the several views.

The draw-head A may be of the general construction and contour shown in the drawings. Its bottom is constructed with a narrow longitudinal slot, a , and its top wall has a similar 55 narrow longitudinal slot, a' . These slots are in the same vertical planes, and are made wide enough to admit of free play of the coupling-pin B, which is designed to extend through said slots across the cavity of the draw-head. 60 The coupling-pin is constructed with a cross-bar, B', near its upper end, which is fitted in vertical grooves c in the adjacent sides of the guide-posts C C, formed or secured upon the top of the draw-head. The coupling-pin is supported by its cross-bar and the guides, but can 65 freely swing, said cross-bar serving as a pivot. The guide-grooves c are about in line with the forward ends of the slots a a' , so that as the pin is drawn upon by link D it will rest solidly 70 against the ends of said slots. The guide-grooves are open on top in order that the pin may be withdrawn and introduced. Means are provided to prevent the pin from being withdrawn accidentally, and these means consist, 75 in this instance, of spring-clasps C' C', hinged at their rear ends to the respective guide-bars, and provided with snaps at their forward ends to lock on the guide-bars.

A chain, E, attached to the head of the coupling-pin passes upward through the handle of the lifter-rod F, and is secured to the top of the car. The lifter-rod slides in staples or other guides in the end of the car, and is, in this instance, constructed with a bifurcated 85 lower end, so that it may stand with its prongs on the respective guide-bars C C and find a support thereon when in its lowest position.

A lever, G, pivoted to one of the prongs of the lifter-rod and fulcrumed by a pin, g, to the 90 end of the car, extends laterally to one side of the car, while a similar lever, G', pivoted to the other prong of the lifter-rod and fulcrumed by a stud, g', on the end of the car, extends laterally to the other side of such car. 95

In order that the levers G G' may be located at any convenient height, I form a series of holes, h, in the end of the car, in either of which the fulcra-pins may be placed. The holes in the levers through which the fulcra-pins pass 100 are somewhat elongated, to provide for the required end-play of the said levers.

- The operation of our coupling is as follows, supposing the position of the parts to be as shown in Fig. 1, except that there is no link in the draw-head: If, now, a car with a link 5 in its draw-head approach, the link thereof will enter the draw-head, and in doing so push the coupling-pin back before it until the end of the link passes the end of said pin, when the latter will immediately swing forward, confining the link so that it cannot be withdrawn. The link may be disengaged by lifting the coupling-pin to the position shown in Fig. 2, and this may be accomplished by lifting the lifter-rod from a point on the top of the car, or from 10 either side thereof, by operating one or the other of the levers G and G'.
It will be seen that our invention obviates the necessity of going between the cars for uncoupling purposes.
20 This improved car-coupling will operate with the ordinary pin-and-link coupling now in common use.
If the cavity of the draw-head be made comparatively shallow, the link will be carried in

an approximately horizontal position, so as to 25 insure the automatic coupling of cars. Crooked links must be used when coupling cars of uneven height.

Having thus described our invention, what we claim as new is—

1. The combination, substantially as before set forth, of the slotted draw-head, the swinging coupling-pin constructed with a cross-bar near its upper end, the vertical grooved guides, the chain, and the lifter-rod. 35

2. The combination, substantially as before set forth, of the slotted draw-head, the swinging coupling-pin constructed with a cross-bar near its upper end, the vertical grooved guides, the chain, the lifter-rod, and the levers extending to the respective sides of the car. 40

In testimony whereof we affix our signatures in presence of two witnesses.

JOHN W. GILBERT.
JOHN A. PRATHER.
